UNITED STATES PATENT OFFICE.

WILLIAM H. WYATT, OF ST. LOUIS, MISSOURI.

RAIL CHAIR AND CLAMP.

Application filed August 11, 1924. Serial No. 731,411.

To all whom it may concern:

Be it known that I, WILLIAM H. WYATT, a citizen of the United States, residing at St. Louis and State of Missouri, have invented new and useful Improvements in Rail Chairs and Clamps, of which the following is a specification.

My present invention has reference to a rail fastener, and has for its object the production of a combined tie plate and rail chair of such construction as to positively prevent the vertical, lateral or tilting movement of a rail on the supporting ties therefor.

With the above broadly stated object in view and others which will appear as the nature of the invention is better understood, the improvement resides in the construction, combination and operative association of elements such as is disclosed by the drawing which accompanies and which forms part of this application.

In the drawing:—

Figure 1 is a perspective view of the rail fastener.

Figure 2 is an approximately central transverse sectional view therethrough, the rail being in section.

My improvement is designed to be arranged on as many ties 1 for rails 2 as may be found desirable or essential in holding the rails properly spaced and for preventing the vertical, lateral or tilting movement of the rails and also to prevent the undue creeping of the rails toward or away from each other.

The improvement contemplates the employment of a base plate 3 arranged longitudinally of the tie 1 and secured thereto by spikes 4. The base plate 3, at a suitable distance inward from its ends is formed with side flanges 5 that embrace the sides of the tie 1. These flanges 5, adjacent to their ends, are notched, and through these notches there are passed securing means 6 that enter the tie.

Integrally formed with the base 3 and with the side flanges 5 there are outstanding longitudinally disposed thickened portions or enlargements 7, each of which having its end formed with an inwardly directed angularly disposed flange 8 respectively, whose ends are in contacting engagement with the opposite sides of the web of

the rail 2 and whose lower edges are in engagement with the angular upper faces and rounded ends of the base flanges of the said rail 2.

Integrally formed on the base 3, between the outer flanges 8, there is a brace lug 9, the same having its inner and lower wall disposed at an angle to overlie the base flange of the rail, its inner face contacting with the web of the rail and its upper edge underlying the head of the rail. Between the flanges and the lug, the base 3 is provided with openings through which are passed spikes 10 that enter the ties 1 and that have their heads engaging with the base flanges of the rail 2.

The efficiency of the improvement as well as the advantages thereof will, it is thought, be apparent from the foregoing to those skilled in the art to which such inventions relate.

Having described the invention, I claim:—

1. A railroad fastener including a base plate designed to be arranged on and spiked to a tie and to support a rail thereon, said base plate having flanged sides also secured to the sides of the tie, inwardly directed rail engaging flanges on the sides of the base, a brace lug between the flanges on the outer side of the rail and on which the head of the rail rests, and spikes passing through the base between the flanges and lug and engaging with the base flanges of the rail.

2. In combination with a railway rail and a supporting tie therefor, of a rail fastener, comprising a base plate spiked to the tie and on which the rail rests, said base plate, inward of its ends, having depending side flanges arranged against the sides of the tie and notched for the reception of securing means, each of said flanges being thickened outwardly at the center thereof and provided with angular inwardly directed flanges to overlie the base flange of a rail and to contact with the web thereof, a brace lug formed on the base plate between the outer rail engaging flanges and on which the head of the rail rests, and headed members passing through the base between the flanges and brace lug and having their heads overlying and contacting with the base flange of the rails.

In testimony whereof I affix my signature.
WILLIAM H. WYATT.
